UNITED STATES PATENT OFFICE.

HUGO LOEWENBACH, OF MILWAUKEE, WISCONSIN.

BOWLING-ALLEY.

1,293,487.

Specification of Letters Patent.

Patented Feb. 4, 1919.

Application filed February 7, 1918. Serial No. 215,797.

To all whom it may concern:

Be it known that I, HUGO LOEWENBACH, a citizen of the United States, and resident of Milwaukee, in the county of Milwaukee and State of Wisconsin, have invented certain new and useful Improvements in Bowling-Alleys; and I do hereby declare that the following is a full, clear, and exact description thereof.

10 My invention has for its general object to provide a simple, economical and effective pin-setting mechanism for bowling alleys, it being of that general type as disclosed in my Patent No. 1,239,280, dated September 4, 15 1917, for improvements in pin-setting mechanism.

The specific object of my present invention is to provide a setting mechanism which will permit freedom of movement of the pins when struck by the ball, thus rendering the effect of the blow upon all pins similar to that in the ordinary game where the pins are spotted upon the floor.

20 With the above objects in view the invention consists in certain peculiarities of construction and combination of mechanical elements as hereinafter set forth with reference to the accompanying illustrations and subsequently claimed.

30 In the drawings—

Figure 1 represents a sectional elevation of a fragment of a pin of a bowling alley embodying the features of my invention, the section being indicated by line 1—1 of 35 Fig. 2;

Fig. 2, a plan view of the same with the bowling pin in section, and

Fig. 3, a diagram view showing the general arrangement of a group of pins.

40 Referring by characters to the drawings, 1 represents a supporting bed for the pins having a shouldered seat 2 therein, the same in this case being illustrated in the form of a recess which has a circular throat portion 2' that is adapted to receive a proportionately smaller circular base 3 of a pin 4. The seat 2 is also formed with an aperture 2'', through which a flexible cord 5 passes, that is connected to the base of the pin and, 45 in this instance, is shown trained around a sheave 6. This cord is attached to a suitable pin-setting mechanism 21, such, for example, as is disclosed in Patent No. 1239280 before mentioned.

50 Spaced above the bed 1 is the bowling alley floor 7, which floor is formed with an

elongated pin-guiding slot 8 therein, the base of the same being alined with the pin-receiving shouldered seat 2. This slot may have the general outline of the pin but is 60 of slightly greater area than the same so as to permit freedom of movement of said pin when the latter is struck by the ball at an unknown angle. Attention will be directed to the fact that, when the pin is upstanding 65 from the floor line, it takes the shape of the standard type and the false base section 3' is reduced and merged at this point into an oval bottom section 3'', which section constitutes in effect a roller that is interposed between the bed and floor 7.

It will also be observed that the pin at its greatest diameter in cross-section is of a dimension which will cause it to project into the slot 8 when said pin is in a down position resting upon the bed 1. Thus the slot confines the pin to a limited degree, but at the same time permits it to fall a certain distance at any angle which will correspond to the angle of the blow that it is struck 80 by the ball, for example, as is indicated by the arrows x , y , that is, if the pin is struck at the point x , it may fall at the angle indicated by the arrow y , which is out of alinement with the elongated guide slot 8. However, before the pin finally comes to rest upon the bed, it will be observed that it will contact with one wall of the slot 8, which wall will act as a deflector to throw the pin into its dead position as indicated in dotted 90 lines 4', Fig. 2. When the pin has been knocked down, the floor is cleared at the point of its fall, whereby the ball may travel in any direction to contact with other standing pins and it will be observed that the 95 falling pin, if struck at the proper angle, will contact with the pins standing whereby a "strike" will be effected. This universal floating movement of the pin incidental to its being struck by the ball is an important 100 feature of my invention and obviates the mechanical limitations of the bowling game wherein the pins are fixedly hinged.

When the pin is downed, it will be observed that it will be confined in practical 105 alinement with the guide slot 8 as previously stated, by the loose fit between the pin and said slot, and it is further confined by the limited scope of movement permitted by the slack in the pin-setting cord 5.

When it is desired to reset the pins obviously the resetting mechanism is operated

by hand from the rear of the floor and the game is again ready to be played.

An important function of the shouldered seat 2 of the pin base is that it confines the base of the pin when said pin is struck by the ball to a limited degree, whereby the pin oscillates a certain amount with the shouldered seat as a fulcrum prior to its nesting down into the slot 8. Thus the various angles indicated by the dotted lines in Fig. 2 may be assumed upon the initial fall of the pin.

The diagram view, Fig. 3, illustrates one of the ordinary set-ups of a group of pins and it is manifest that, while I have described only one of the pin mechanisms, in practice a group of them are arranged according to my invention similar to the group mentioned. Hence, if the first pin of the series is struck correctly it is possible to down the entire group of pins by one contacting with the other in the same manner as the blow would affect a group of pins simply spotted upon an alley floor.

I direct attention to the fact that the edges of the slot 8 may be reinforced by metal to prevent breakage or wear which will occur to a more or less degree by the surface of the pin contacting with said edges. The reinforcing may be dispensed with, however, where hardwood is employed.

I claim:

1. A bowling alley comprising a pin, a supporting bed therefor having a shouldered seat adapted to receive the pin base, a floor above the bed having an elongated guide slot therein positioned over the bed seat, through which slot the pin is adapted to project, and pin-setting mechanism connected to the base of said pin.

Copies of this patent may be obtained for five cents each, by addressing the "Commissioner of Patents, Washington, D. C."

2. A bowling alley comprising a pin, a supporting bed therefor having a shouldered seat adapted to receive a pin base, a floor positioned above the base having an elongated slot therein associated with the bed seat and permitting limited free movement of the pin in any direction incidental to the same being knocked down, and flexible means for resetting the pin.

3. A bowling alley comprising a pin having a flat base of circular contour, a supporting bed therefor having a shouldered seat of larger diameter than the pin base and adapted to receive the same, a floor positioned above the bed provided with an elongated slot associated with the pin base, the slot being of such dimensions as to permit a limited free movement of the pin in any direction when rocked upon its shouldered seat but adapted to ultimately guide the pin to its dead point of rest upon the bed, and flexible means connected to the pin base for resetting the same.

4. A bowling alley comprising a pin, a supporting bed therefor, means associated with the pin base to permit the same to rock thereon to a limited degree, a floor positioned above the bed provided with an elongated slot associated with the pin base, the slot being of such dimensions as to permit a limited free movement of the pin in any direction when rocked upon its seat but adapted to ultimately guide the pin to its point of rest upon the bed, and means for resetting the same.

In testimony that I claim the foregoing I have hereunto set my hand at Milwaukee, in the county of Milwaukee and State of Wisconsin.

HUGO LOEWENBACH.
